UNITED STATES PATENT OFFICE

HENRY S. MITCHELL, OF PORTLAND, OREGON, AND RALPH V. SCHAFER, OF VANCOUVER, WASHINGTON

DEBARKING MACHINE

Application filed May 22, 1929. Serial No. 365,987.

Our invention relates to machines for removing the bark from relatively light pieces of lumber such as bark slabs and the like.

The object of our invention is to provide a simple and practical machine for removing the bark from relatively light pieces of lumber such as the rounded outer surfaces of the so-called "bark slabs" which are sawed from the log in the mill, or the unsawed logs of relatively small diameter, in order to render the said wood suitable to be used in the manufacture of paper pulp and the like, which is otherwise too small and light to be of any practical value in this respect.

15 A further object of our invention is to provide a debarking machine, provided with a longitudinally concaved cutter head, carrying correspondingly concaved knives, whereby the cutting edge of the knives will conform more or less to the rounded outer surfaces of the wood being debarked so that the knives will be supported along their entire length by the cutter head in order to withstand the severe duty imposed on them when 25 they strike the solid wood portions and knots of the slabs or small logs being operated upon.

A still further object of our invention is to provide a debarking machine of this character adapted by simple means to be adjusted to the thickness of the bark being removed so that the underlying wood will not be touched by the knives of the machine and hence not removed with the bark.

30 35 A further object of our invention is to provide a machine so simple in operation that the slab or timber to be debarked may be placed on the machine and guided during the debarking operation by one man.

40 45 We attain these objects in a debarking machine comprising a frame, a work supporting table on said frame, comprising an elongated casting having sloping sides receding upward to a narrow work-supporting top, one side of the said table being hinged to the said frame, the longitudinal middle of the table provided with a concave depression in which to seat the work, and such depression provided with an opening, a longitudinally concaved cutter head rotatably supported in

said frame on an axis substantially parallel with said table, said cutter-head carrying knives longitudinally concaved to conform with the curvature of the said concaved cutter-head, said knives projecting through said opening on the table, and means for relatively adjusting the table to said axis whereby to vary the depth of cut of said cutter-head.

These and other incidental features, the details of construction and the mode of operation of our invention are hereinafter fully described with reference to the accompanying drawings.

In the drawings:

Fig. 1 shows a front elevation of our debarking machine partly in section and illustrates a wood slab in position on the machine to be operated upon;

Fig. 2 shows a top plan view of our machine with one of the bed plates removed;

Fig. 3 shows a perspective view of the bed plate removed from the machine;

Fig. 4 shows a section taken on the line 4—4 of Fig. 2;

Fig. 5 shows a similar enlarged section to that of Fig. 4 and illustrates a wood slab being operated upon by the machine;

Fig. 6 shows a central longitudinal section of the cutter head removed from the machine and without the knives or knife holding means;

Fig. 7 shows a front elevation of one of the knives removed from the cutter-head; and

Fig. 8 shows similarly the knife holding bar removed from the cutter-head.

With reference to the figures our machine comprises a supporting frame *a* shown in this embodiment of our invention with two similar bark removing elements which are identical and only one of which will be described; similar reference characters indicate similar parts of the other debarking element.

A cutter-head *b* is carried on a horizontal shaft *c* journaled in the frame *a* as at *d* and driven by an electric motor *e*, or other suitable driving means. The cutter head *b* is concave, see Figures 1 and 6, and is provided with longitudinally concaved knives *g*, see Fig. 7, mounted in knife receiving slots *h* and held

therein by bearing bars *i*, see Figs. 5 and 8, and set screws *j*.

A work supporting table *k* is provided, adapted to be hingedly mounted on the frame

5 *a* over the cutter head *b*, on lugs *k'*, as at *k''*, and to be adjustable relative to the cutter-head by means of a set screw *k³* which bears on an oppositely arranged ledge *a'* of the frame so that by adjusting the set screw *k³* the

10 heights of the table *k* are varied relatively to the knives *g* so that the depth to which they will operate on the work may be adjusted.

The work table is provided with a central transverse concave portion *p* in which is 15 formed an aperture *l* through which the cutter head projects. The work table *k* is also beveled on its edges as at *m* to permit a wood slab or the like to be moved longitudinally thereon with a minimum of resistance.

20 In the operation of our machine a wood slab indicated by *x* is moved longitudinally over the concave portion of the work table by an attendant so that the knives of the cutter-head may operate upon the bark to remove

25 it. In order that all portions of the slab will be operated upon, the attendant rocks the slab sideways in order to bring every portion of it into contact with the cutter head, see Fig. 5, and the beveled or sloping sides *m* permit the operator to bring his hands into close

30 proximity with the cutter head, thereby to facilitate the manipulation of the slab in bringing every portion into contact with the cutter head.

35 Thus, by this construction we have provided a slab debarking machine which is simple of construction and operation and by which the bark covering of wood slabs or logs of relatively small diameter may be rapidly 40 and economically operated upon.

Also, by providing a concave cutter head for holding and supporting the concaved knives, the knives are supported along their entire length and thus strengthened in order 45 to withstand the heavy duty to which they are subjected.

Further, the strain on the cutter-head is so severe that ordinary cast iron or cast steel has not the required toughness and we have 50 found it preferable to use mild steel of a similar metal more adapted to withstand the shock of the impact of the knives on the work.

We have shown only one means for relatively adjusting the depth of cut of the knives 55 of the cutter-head, believing that the means so provided are most practical from a mechanical standpoint, with regard to simplicity, convenience, efficiency and economy in construction. But it is self-evident that if 60 simplicity is not to cut any figure in the construction of our debarking machine the parts by which the said variation in depth of cut of the cutter-head is effected, could be readily rearranged so that instead of making the table adjustable towards and from a stationary

axis of rotation of the cutter-head, the table could be made stationary, and said axis of rotation adjustable and in that way accomplish the same end.

We claim:

1. In a debarking machine of the character described, in combination with a rotary cutter head, of a work supporting table extending parallel with the axis of the cutter head, said table provided with a central transverse work supporting depression, said depression having an opening through which the cutter head projects, the side walls of said depression narrowing upwardly to reduce the area of contact between the work supporting depression and the work, the top of the supporting table extending laterally on both sides of but receding from said depression into a narrow ledge the depending sides of which are sloped, whereby to permit the hands of the operator to be brought into close proximity with the cutter head while manipulating the work.

2. In a debarking machine of the character described, in combination with a standard and rotary cutter head, of a work supporting table hinged on one side to said standard and extending parallel with the axis of the cutter head, said table provided with a central transverse work supporting depression, said depression having an opening through which the cutter head projects, a set screw threaded through the other side of said table and bearing on said standard for adjusting the top relatively to the cutter head, the side walls of said depression narrowing upwardly to reduce the area of contact between the work supporting depression and the work, the top of the supporting table extending laterally on both sides of but receding from said depression into a narrow ledge the depending sides of which are sloped, whereby to permit the hands of the operator to be brought into close proximity with the cutter head while manipulating the work.
